COMBINED COMB, BRUSH, AND CURLER

Siegfried Behr, Flushing, N. Y., assignor to Ben Hur Products, Inc., New York, N. Y., a corporation of New York

Application March 14, 1940, Serial No. 323,911

6 Claims. (Cl. 132—88)

This invention relates generally to ladies' toilet articles and more particularly to a combined comb, brush, and curler.

An object of the invention is to provide a device of this kind that is simple and compact in construction and economical to manufacture.

Another object is to provide a device of this kind that is pleasing, attractive and graceful in appearance.

Another object is to provide such a device that is sanitary.

Yet another object is to provide a device of this kind in which the brush member is readily moved to inoperative position for cleaning purposes.

The above and other objects and advantages will be obvious from the description of the invention to follow taken in connection with the accompanying drawing in which—

Fig. 1 is a side view of the improved, comb, brush and curler device.

Fig. 2 is a sectional view taken on the plane of the line 2—2 of Fig. 1 with the brush stem omitted.

Fig. 3 is a sectional view taken on the plane of the line 3—3 of Fig. 1.

Fig. 4 is a side view of one end of the brush showing the looped end of the stem.

Fig. 5 is a side view showing a modified form of curler or handle.

Fig. 6 is a top plan view of part of the device of Fig. 5.

The improved device includes a comb 10 and a curler 11 integrally formed and preferably made of moldable plastic material such as acetate, plastic or the like. The comb comprises a back portion 12 and teeth 13. The back portion 12 is formed with a slotted or cut-away portion 14 at its upper edge. An upstanding post or bearing member 15 is formed on the back portion 12 at the rear of the slotted portion 14 and a similar post or stud 16 at the front of the slotted portion.

The curler member 11 forms the handle for the comb and extends rearwardly from the upper edge of the comb. The curler is circular in cross section and tapers from the comb to its free end resulting in what is called a "rat-tail" curler.

A brush member 17 is positioned in the slotted or cut-away portion 14 on the top of the back portion 12. This brush consists of a stem 18 formed of twisted wires between which are secured the bristles 19. The bristles are radially positioned on the stem and form a brush circular in cross section. Looped end 18' of the stem 18 is hinged to the post or bearing member 15

by means of a pivot pin or eyelet 20. It will be noticed that the hinge pin is positioned so that a portion of the bristles 19 project downwardly over and span the upper edge of the teeth and back portion 12 of the comb. The opposite end of the stem 18 is free and is slipped under and behind the overhanging lip portion 21 of a slot 22 formed in the post or stud portion 16. The inherent elasticity of the material forming the comb permits the free end of the stem to ride down over, under and behind the lip 21 where it is held in position by the wall of said lip portion.

When it is desired to clean the brush, it is swung upwardly to the position shown in dotted lines in Fig. 1. When the brush is in downward operative position as shown in full lines in Fig. 1, the stem 18 is more or less hidden from view and only a portion of the bristles extend above the top of the comb giving the entire device a graceful and compact appearance, and the radiating bristles afford a brushing action following the combing action of the teeth of the comb.

The construction and arrangement of the brush relative to the comb permit the comb and brush to be grasped by the hand when the curler is being used to curl the hair.

In Fig. 5, the curler device is in the form of a bifurcated or two piece tapered handle 11' which is hinged to the member 15 by means of a pivot pin 23. The curler 11' may be swung downwardly and up over the teeth to collapsed position as shown in dotted lines in Fig. 5. This results in a very compact device which can be carried in a lady's handbag etc.

I claim:

1. A lady's toilet article comprising a comb member having its back portions slotted, a curler member forming an extension of the comb and formed integrally therewith and a brush member supported hingedly and releasably in said slotted portion.

2. A lady's toilet article comprising a comb member having its back portion slotted, a post formed on said back portion at each end of the slotted portion, a tapered extension formed integrally with said comb and forming a curler and a brush member having one end hinged to one of said posts and its other end being adapted to be releasably held by the other of said posts.

3. A lady's toilet article comprising a comb member formed of plastic material including a back portion having a cut-away portion and a plurality of teeth, a tapered extension forming a handle for said comb and a brush member cir-

cular in cross section and having its stem positioned in said cut-away portion so that a portion of the brush bristles extend downwardly over the back portion of the comb and angularly relative to the teeth.

5. A lady's toilet article comprising a comb member formed of plastic material and with its back formed with a cut-away portion terminating in an upstanding post at each end, one of 10 said posts being formed with a slot having an overhanging lip and a brush member having a central stem and radiating bristles on the stem, one end of said stem being hinged to one of said posts and its other free end being adapted 15 to be inserted into the slot in the other post and to be held in inserted position by the lip of said slot.

6. A lady's toilet article comprising a comb member formed of plastic material and with its 20 back formed with a cut-away portion terminating in an upstanding post at each end, one of said posts being formed with a slot having an overhanging lip, an integral tapered extension circular in cross section forming a handle for said comb and being adapted to serve as a hair curler 25 and a brush member circular in cross section having an axial stem with bristles radiating therefrom, one end of said stem being hinged

to one of said posts and its other free end being adapted to be inserted into the slot in the other post and to be held in inserted position by the lip of said slot, said stem being positioned in the cut-away portion of the comb so that a portion of 5 the bristles extend downwardly over the back portion of the comb and angularly relative to the teeth of the comb.

7. A lady's toilet article comprising a comb member formed of plastic material and with its 10 back formed with a cut-away portion terminating in an upstanding post at each end, one of said posts being formed with a slot having an overhanging lip, a bifurcated tapered extension forming a handle for said comb and being 15 adapted to serve as a curler for the hair and a brush member circular in cross section having an axial stem with bristles radiating therefrom, one end of said stem formed with a loop and hinged to one of said posts and its other end being 20 free and adapted to be inserted into the slot in the other post and to be held in inserted position by the lip of said slot, said stem being positioned in the cut-away portion of the comb so that a portion of the bristles extend downwardly 25 over the upper portion of the teeth of the comb and at an angle thereto.
